UNITED STATES PATENT OFFICE

161,350

PLAQUE

Louis Leventhal, New York, N. Y., assignor of
one-half to Nathan Freyer, New York, N. Y.

Application July 8, 1949, Serial No. 3,781

Term of patent 7 years

(Cl. 29—23)

To all whom it may concern:

Be it known that I, Louis Leventhal, a citizen of the United States and a resident of New York city, in the Borough of the Bronx, county of Bronx, and State of New York, have invented a new, original, and ornamental Design for Plaque, of which the following is a specification, reference being had to the accompanying drawings, forming part thereof.

In the drawings:

Fig. 1 is a front elevational view of a plaque showing my new design.

Fig. 2 is a vertical sectional view taken approximately on line 2—2 of Fig. 1.

Fig. 3 is a bottom end view thereof.

I claim:

The ornamental design for a plaque, substantially as shown.

LOUIS LEVENTHAL.
